US0D1090702S

(12) **United States Design Patent** (10) **Patent No.:** **US D1,090,702 S**
(45) **Date of Patent:** **** Aug. 26, 2025**

(54) **DISPENSING MACHINE**

(71) Applicant: **Trinity Axis Inc.**, Harleysville, PA (US)

(72) Inventors: **Jeremiah Divyan David**, Tamil Nadu (IN); **David D. Davidar**, Schwenksville, PA (US); **Arunkumar G**, Tamilnadu (IN); **Loganathan B**, Tamilnadu (IN); **Periasamy G**, Tamilnadu (IN); **Vignesh Kumar V**, Tamilnadu (IN); **Dinesh Raj**, Chennai (IN); **Carlos Terminel**, San Jose, CA (US); **Cole Derby**, San Jose, CA (US); **Dan Harden**, San Jose, CA (US); **Wei Gu**, San Jose, CA (US)

(73) Assignee: **Trinity Axis Inc.**, Harleysville, PA (US)

(**) Term: **15 Years**

(21) Appl. No.: **29/883,407**

(22) Filed: **Jan. 27, 2023**

(51) LOC (15) Cl. **20-01**

(52) U.S. Cl. **USPC .....** **D20/1**

(58) **Field of Classification Search**

(57) **CLAIM**

The ornamental design for a dispensing machine, as shown and described.

DESCRIPTION

FIG. 1 is a front perspective view of a dispensing machine; FIG. 2 is a front elevation view thereof; FIG. 3 is a rear elevation view thereof; FIG. 4 is a right side view thereof; FIG. 5 is a left side view thereof; FIG. 6 is a top view thereof; and, FIG. 7 is a bottom view thereof. The broken lines depict portions of the dispensing machine and form no part of the claimed design.

1 Claim, 7 Drawing Sheets
